3,164,315 CARTON CONSTRUCTION

Norman A. Kelly, Wayne Township, Kosciusko County, Ind., assignor to Crystal Preforming and Packaging, Inc., Warsaw, Ind., a corporation of Indiana
Filed Oct. 3, 1962, Ser. No. 228,118
3 Claims. (Cl. 229—17)

This invention relates in general to a container construction and, more particularly, to a type thereof which is fabricated from coated paperboard, which is capable of holding liquids, such as milk or juice, and which has a closure structure including a self-contained pouring spout.

Coated paperboard containers or cartons have been widely and successfully used for many years, both commercially and in private homes. Examples of such cartons are disclosed in my copending patent applications, Serial No. 111,028, now Patent No. 3,118,586, and Serial No. 146,964. Many different types of coatings, including thermoplastics, have been used for rendering the paperboard containers liquid proof. Polyethylene has been found to be well suited for this purpose because it produces tough, watertight surfaces which can be sealed together by heating or otherwise softening the plastic material on the surfaces to be sealed, and pressing such surfaces together. However, it will be understood that the specific reference herein to a specific kind of plastic and a method of effecting said sealing is for illustrative purposes only.

Many problems, which are discussed in detail in the above-identified patent applications, have been encountered during the development of plastic coated cartons or containers, particularly where the plastic coating is utilized to seal the closure structure after the container is filled. Principally, it has been difficult to obtain a good seal which can be easily and manually, but not accidentally, broken in order to remove the contents from the carton. Secondly, it has been difficult to provide an integral pouring spout which does not have an unsanitary, ragged or fuzzy lip resulting from the breaking of the seal. Moreover, it has been found difficult to satisfactorily overcome the above-mentioned problems while, at the same time, providing a closure structure which can be automatically closed and sealed by moderately priced machinery which can be purchased by, and efficiently used in, the average small dairy, as well as large dairies.

Accordingly, the primary objects of this invention include the provision of a plastic-coated container having a closure structure which can easily be preformed by machinery of modest size and moderate cost, which permits easy filling of the container, which can be automatically closed and sealed by a relatively uncomplicated machine, which is neat in appearance and leakproof, which has an easily accessible and integral spout, and which can be easily and manually (but not accidentally) opened for immediate use without producing an unsightly, unsanitary and ragged edge at the outer end of the pouring spout.

A further object of this invention has been the provision of a carton construction, including the aforesaid closure structure, which can be easily and economically fabricated from coated paperboard and which requires no more material than existing carton constructions of the same general type.

Other objects and purposes of this invention will become apparent to persons familiar with this type of product upon reading the following descriptive material and examining the accompanying drawings, in which:

FIGURE 1 is a broken perspective view of a carton construction embodying the invention.

FIGURE 2 is a broken plan view of a carton blank from which said carton construction can be formed.

2

FIGURE 3 is a fragment of the carton blank shown in FIGURE 2, as viewed from the opposite side thereof.

FIGURE 4 is a top view of the closure structure of said carton in its open position.

5 FIGURE 5 is a sectional view taken along the line V—V in FIGURE 4, with the closure structure in its closed position.

FIGURE 6 is a fragment of FIGURE 5 with the closure structure in a partially open position.

10 FIGURE 7 is a fragmentary, side elevational view of the carton showing the closure structure in the open position.

FIGURE 8 is a perspective view of a fragment of the carton disclosing the bottom thereof.

15 FIGURE 9 is a sectional view taken along the line IX—IX in FIGURE 8.

FIGURE 10 is a side elevational view of a fragment of said carton showing the bottom structure thereof in a partially closed position.

20 FIGURE 11 is a fragment of FIGURE 2 showing an alternate construction for the pouring spout of the carton.

For convenience in description, the terms "upper," "lower" and words of similar import will have reference to the carton and its closure structure as appearing in 25 FIGURES 1 and 7. The terms "front," "rear" and words of similar import will have reference, respectively, to the left and right sides of the carton and its closure structure, as appearing in FIGURES 5 and 7. The terms "inner," "outer" and derivatives thereof will have reference to the 30 geometric center of said carton or said closure structure and parts thereof.

General Description

The objects and purposes of the invention, including those set forth above, have been met by providing a carton construction fashioned from a flat blank which is cut from a coated sheet of paperboard or the like and simultaneously scored. In this embodiment, the coating on said paperboard preferably contains at least a very substantial amount of plastic material which is preferably heat-sealable. The carton has four side walls and a bottom wall arranged to define a rectangular container which is open at one end and which preferably has a substantially square cross section. The carton has a closure structure which is formed from four end panels integral with the ends of the side walls at the open end of the carton. In a preferred embodiment, the end panels are of such size and shape that they form a gabled closure structure when they are folded towards each other.

45 The upper portions of the end panels are scored to form an upright rib along the upper edge of the gable when it is in its closed position. One of said end panels has an integral flap which extends around and seals the rib. By 50 providing an appropriate cut in one end panel and by 55 providing antisealant means on several end panels, it is possible to open easily, but not accidentally, the closure structure in order to form an integral pouring spout.

Detailed Description

The carton 10 (FIGURE 1), which illustrates a preferred embodiment of the invention, is fashioned from a flat carton blank 11 (FIGURE 2), which is cut from a sheet of coated paperboard or the like and simultaneously scored. In a preferred embodiment, the sheet material from which the carton blank is cut may consist of heavy paper stock or other suitable sheet material which is sufficiently stiff to be self-supporting and capable of withstanding reasonable amounts of rough handling without collapsing, particularly after the blank has been fashioned into the closed container 10. By way of example, the sheet material may be coated with a synthetic plastic composition, such as polyethylene, which may be compounded

with other ingredients or additives for the purpose of improving the adhesive or other qualities of the composition for the intended purposes. It is, however, important to this invention that the plastic coating be capable of achieving a strong adhesive bond with the paper stock and a strong cohesive bond when portions of the coated sheet material are heated, or otherwise softened, and then firmly held together while the seal forms therebetween. It is also contemplated that the coating on the paperboard can be either a pressure-sensitive material or a combined heat and pressure-sensitive material, whereby the sealing together of the end panels is effected at least partially by pressure. Under some circumstances, it may be desirable to use a plastic coating which is caused to form the seal by applying a solvent or an adhesive to the surfaces between which the seal is desired.

The blank 11 (FIGURE 2) has a plurality of transverse, parallel and spaced fold or scored lines 12, 13, 14 and 15 which divide the blank 11 into four side walls 16, 17, 18 and 19, respectively, and an edge strip 20 which is integral with the side panel 19 along the scored line 15. The blank 11 is fashioned into a tube of substantially rectangular cross section by heating the edge strip 20 and the lengthwise free edge portion of the side wall 16, and thereafter pressing them together.

A bottom wall 24, FIGURES 1, 8 and 9, is formed on one end of said tube by folding the lower end panels 25, 26, 27 and 28 (FIGURE 2) inwardly toward each other. The scored lines 12a, 13a, 14a and 15a, which are downward extensions of the scored lines 12, 13, 14 and 15, respectively, define the junctions between the integral, lower end panels. The converging scored lines 31 and 32 on the lower end panels 26 and 28, respectively, facilitate the folding of the lower end panels to form the bottom wall 24. The lower end panel 25 is provided with an integral tab 33 which extends beyond the lower ends of the other lower end panels and which overlaps the lower end of the end panel 27, as shown in FIGURES 8 and 9, and thereby forms a seal when the bottom wall is formed.

The carton blank 11 (FIGURE 2) has a lower, lengthwise fold line 34 which is perpendicular to the scored lines 12, 13, 14 and 15, and which defines the junction of the lower end panels with the side walls. An upper fold line 36, which is parallel with the fold line 34, defines the junction between the side walls and the upper end panels 37, 38, 39 and 40, from which the closure structure 41 (FIGURE 1) is formed. Said upper end panels are integral with each other, and their junctions are defined by the score lines 12b, 13b, 14b and 15b which are upward extensions of the score lines 12, 13, 14 and 15, respectively.

A fold line 43 (FIGURE 2), which is parallel with the fold line 36, is provided along and near to the upper edges of the upper end panels so that it intersects perpendicularly the score lines 12b, 13b, 14b and 15b. A pair of converging score lines 44 and 45 are provided in the upper end panel 38 so that they converge from the intersections of the fold line 36 with the score lines 12b and 13b toward a point on the fold line 43 approximately midway between the score lines 12b and 13b. A similar pair of converging score lines 47 and 48 are provided in a similar manner in the end panel 40. Fold lines 51 and 52, which are of relatively short length, extend from the convergence of score lines 44, 45 and 47, 48, respectively, to the upper edges of their end panels 38 and 40, respectively. A pair of converging score lines 53 and 54 extend respectively from the intersections of the score lines 13b and 14b with the fold line 36 to a point in the upper edge of the end panel 39 midway between said score lines 13b and 14b.

The upper, substantially rectangular portions 56, 57, 58 and 59 (FIGURE 2) of the upper end panels 37, 38, 39 and 40, respectively, which are disposed above the fold line 43, are bent along said fold line 43 during the

closure-forming operation so that they assume substantially parallel positions (FIGURE 5) and thusly provide a rib 62 (FIGURE 1) along the upper edge of the gabled closure structure 41.

5 A cover flap 63 (FIGURE 2) is preferably integral with the upper end panel 37 and extends substantially beyond the upper edges of the other upper end panels. A pair of substantially parallel fold lines 65 and 66, which are preferably parallel with fold line 43, are scored in the flap 63 for facilitating its bending over the rib 62 (FIGURES 1 and 5).

The inner surface (FIGURE 3) on the edge portion 58 of the end panel 39 is covered or coated, substantially throughout its length, with an antisealing strip or material 67, which remains non-adhesive when the edge portions 56, 57, 58 and 59 are heated, or otherwise treated, for the purpose of rendering the coating material thereon adhesive prior to the sealing operation. Accordingly, no seal is formed between substantially all of the engaging inner surfaces on the edge portion 58 and the parts 57a and 59a of the edge portions 57 and 59, which are against edge portion 58 during the sealing operation. In order to eliminate any possibility of accidental leakage or seepage between the edge portion 58 and the edge parts 57a and 59a adjacent the opposite ends of edge portion 58, the ends of the edge portion 58 are not covered with the antisealing strip 67, as shown in FIGURE 3. Accordingly, controlled sealing does occur at the ends of the edge portion 58. The flap 63 is sealed to the outer surface of the edge portion 58 during the sealing operation and thereby prevents leakage past the strip 67 between the ends of the edge portion 58.

In order to facilitate opening of the closure structure 41, the outer surface on the upper edge portion 58 of the end panel 39 is provided with a substantially U-shaped cut 68 (FIGURE 2) which penetrates the plastic coating on the outer surface of the blank 11. Said cut 68 extends substantially along the adjacent portions of the fold line 43 and scored lines 13b and 14b. The strip 69 of plastic coating defined by the cut 68 in the edge portion 58 is pulled away from the paperboard 71 (FIGURE 6) beneath the coating strip 69 when the cover flap 63 is pulled upwardly away from the rib 62 to open the closure structure 41. Because the exposed paperboard is on the outer side of the panel 58, hence of the pouring spout 72 (FIGURES 4 and 7), the exposed paperboard does not interfere with the operation of the spout. The antisealing strip 67 on the inner lip of said spout 72 provides a clean pouring edge therefor.

50 The amount of heat which reaches the outer surfaces on the edge portions 57 and 59, and/or the amount of sealing which occurs between the parts 57a, 57b and 59a, 59b, may be somewhat less than the heating and sealing which occurs between the inner surfaces on the edge portion 56 and the edge parts 57b and 59b, in order to facilitate the opening of the spout 72. That is, it is important that the parts 57b and 59b of the edge portions 57 and 59 remain connected or sealed to the edge portion 56 while the closure structure 41 is opened and the spout 72 is formed. Also, it is important that the spout 72 can be easily and manually moved from its closed (FIGURE 6) position to its open (FIGURE 4) position by using the thumb and forefinger, for example.

65

Operation

The assembly and operation of the carton 19 and its closure structure 41 are probably evident from the foregoing descriptive materials. Briefly, the blank 11 is first formed into a tube and then into a substantially rectangular and upwardly opening container having side walls 16, 17, 18 and 19 and a bottom wall 24. The closure structure 41 is formed by urging the upper end walls 38 and 40 toward each other so that said upper end panels are bent along the fold lines 36 and 43 and along the con-

verging score lines 44, 45, 47 and 48. Heat is applied to the flap 63 and to the edge portions 56, 57, 58 and 59 so that at least portions of the plastic material thereon are rendered adhesive. Thereafter, the edge portions 56, 57, 58 and 59 are moved into adjacent parallel positions, as appearing in FIGURES 5 and 6, after which the cover flap 63 is folded around the rib 62 and they are pressed tightly together. The resultant seal of the cover flap 63 and rib 62 creates a liquid-proof closure structure 41 which will not open accidentally, even when it is roughly treated. 10

The closure structure 41 is easily opened by moving the free end of the cover flap 63 upwardly into its FIGURE 6 position and away from the edge portion 58. During this operation, the coating strip 69 is pulled or peeled with the flap 63 away from the edge portion 58. The spout 72 can then be opened by squeezing the front portions of the end panels 38 and 40 between the thumb and forefinger. 15

After the spout 72 has been used, it can be manually moved back into its FIGURE 6 position and the cover flap 63 can be folded over the rib 62. Following the sealing operation, the cover flap 63 will have a tendency or memory urging it toward its FIGURE 5 position, whereby the closure structure 41 is held in a substantially dustproof and sanitary position. 20

The alternate structure appearing in FIGURE 11 provides a spout 75 having a broad pouring tip 76 instead of the pointed tip appearing in FIGURE 4. The pouring tip is formed on the spout 75 by reducing the convergence 30 of the fold lines 77 and 78 so that they do not meet at the outer edge of the end panel 39a.

Although particular preferred embodiments of the invention have been disclosed above for illustrative purposes, it will be understood that variations or modifications of such disclosure, which come within the scope of the appended claims, are fully contemplated. 35

What is claimed is:

1. In a container construction fashioned from a blank of coated sheet material, said container construction 40 including four side walls and a bottom wall arranged to define a substantially rectangular compartment open at one end thereof, structure for closing the open end of said container construction, comprising:

45 four substantially rectangular panels integral with and extending respectively from the ends of the side walls adjacent the open end of the container construction, the junction between said panels and said side walls being defined by first fold lines lying substantially within a plane parallel with the bottom wall, each panel being coated with a film of thermoplastic material and being connected to the adjacent panels and such connections being defined by second fold lines transverse of said first fold lines, and each panel extending from its first fold line a distance less than the length of the first fold line associated with an adjacent panel;

50 a third fold line extending across each end panel parallel with said first fold lines, the third fold lines defining edge portions on said panels spaced from said first fold lines a distance greater than half the length of a first fold line associated with an adjacent panel;

55 means defining in one panel a pair of fold lines converging from the opposite ends of its first fold line to the midpoint of the free edge of its respective edge portion; means defining in the two panels adjacent said one panel a pair of fold lines converging from the opposite ends of their first fold lines to the midpoints of their respective third fold lines;

60 a flap integral with, and extending from the edge portion of, the panel opposite said one panel, said flap being engageable with the outer surface on the edge portion of said one panel when the edge portions of said panels are substantially perpendicular

6 to said plane and adjacent to each other, and said one panel and said opposite panel are at acute angles to said plane; and means defining a substantially U-shaped cut in said outer surface on said edge portion of said one panel, said cut extending along the adjacent parts of the second and third fold lines on said one end panel and penetrating the film on said outer surface whereby the coating on said surface of said one panel within the zone defined by said cut is removed with said flap when the closure structure is opened. 10

2. The structure of claim 1 wherein said blank is fabricated from paperboard coated with said thermoplastic material;

15 wherein said paperboard is only partially penetrated by said cut throughout its length; and including a nonadhesive covering over the thermoplastic film on the inner surface of the edge portion of said one panel.

3. In a container construction fashioned from a blank of coated sheet material, said container construction including four side walls and a bottom wall arranged to define a substantially rectangular compartment open at one end thereof, structure for closing the open end of said container construction, comprising:

20 four substantially rectangular panels integral with and extending respectively from the ends of the side walls adjacent the open end of the container construction, the junction between said panels and said side walls being defined by first fold lines lying substantially within a plane parallel with the bottom wall, each panel being coated with a film of thermoplastic material and being connected to the adjacent panels and such connections being defined by second fold lines transverse of said first fold lines, and each panel extending from its first fold line a distance less than the length of the first fold line associated with an adjacent panel;

25 a third fold line extending across each end panel parallel with said first fold lines, the third fold lines defining edge portions on said panels spaced from said first fold lines a distance greater than half of the length of a first fold line associated with an adjacent panel;

30 means defining in each of three adjacent panels a pair of fold lines converging from the opposite ends of their first fold lines toward the midpoints of their respective third fold lines, the center pair converging above said midpoint;

35 a flap integral with, and extending from the edge portion of, the fourth one of said panels, said flap being engageable with the outer surface on the edge portion of the center one of said three panels when the edge portions of said panels are substantially perpendicular to said plane and adjacent to each other and said center and fourth panels are at an acute angle to said plane; and

40 means defining a substantially U-shaped cut in said outer surface of said edge portion of said center panel, said cut penetrating the thermoplastic coating on said outer surface and extending along the adjacent parts of the second and third fold lines on said one end panel, whereby the zone defined by said cut is removed with said flap when the closure structure is opened.
